CLAIM

We claim the ornamental design for an inverse love seat, as shown and described.

DESCRIPTION

FIG. 1 is a top front perspective view of an inverse love seat; FIG. 2 is a bottom front perspective view thereof;

FIG. 3 is a front elevation view thereof;

FIG. 4 is a rear elevation view thereof;

FIG. 5 is a left side elevation view thereof;

FIG. 6 is a right side elevation view thereof; FIG. 7 is a bottom plan view thereof;

FIG. 8 is a top plan view thereof; and,

FIG. 9 is a bottom plan view thereof.

The broken line structures in the drawings form no part of the claimed design. Interior surfaces and other portions of the inverse love seat not shown in the illustrated drawings form no part of the claimed design.

1 Claim, 5 Drawing Sheets
